UNITED STATES PATENT OFFICE.

MARYANN D. SEARS, OF LOS ANGELES, CALIFORNIA.

BEDPAN.

Application filed April 12, 1927. Serial No. 183,063.

The object of this invention is to provide a bed pan, of simple and rugged construction, which shall be more sanitary and more convenient than bed pans heretofore in use. It is an object of this invention to provide a bed pan, preferably having an extensive and substantially rectangular flat bottom (hereinafter referred to as a "main" bottom) with a partial cover which is upwardly rounded in a manner favorable to an interfitting of the same between the legs of a user; and, in preferred embodiments of my invention, all parts being preferably formed from sheet metal and suitably enameled or otherwise coated, the said bottom may terminate, at one end, in a flat member interposed between the mentioned main bottom and the mentioned partial cover and adapted to serve as an alternative bottom,—upon which the bed pan may temporarily rest, in an upright position, after it has been used and removed from a bed.

It is a further object of my invention to provide a bed pan from which the contents, regardless of their consistency, can be conveniently and completely removed; and, in preferred embodiments of my invention, the mentioned main bottom may be provided, at the end opposite from the mentioned alternative bottom, with a transverse roll, preferably integral with said bottom and extending entirely across the said bed pan,—either the mentioned partial cover or the mentioned transverse roll being employed as a pouring-edge in the emptying of said pan.

The mentioned partial cover being longitudinally rounded, in a manner adapting the legs of the user to overlie the same, and preferably so cut away as to produce a substantially semi-circular outline, as viewed in plan, a central portion of the mentioned rounded edge may be adapted to serve as a spout or partial-width pouring edge, suitable for use in case the contents must be delivered into a comparatively small opening; and the mentioned transverse roll may be adapted to serve not only as a body rest, during the use of the bed pan, and as full width-pouring edge, enabling the bed pan to be conveniently and completely emptied, rinsed and inspected, but also as an integral handle,—a recurved portion of said transverse roll being conveniently engageable by the fingers. This integral handle is favorable to the removal of the bed pan from a

bed, to a standing of the same, at a bed side, in an upright position, to a carrying of the same, in a dependent position, by one hand, and to an emptying of the same over the partial-width pouring edge or spout provided by the longitudinally rounded partial cover.

Other objects of my invention may be best appreciated from the following description of an illustrative embodiment of my invention, taken in connection with the appended claims and the accompanying drawings, in which

Fig. 1 is a top plan view.

Fig. 2 is a longitudinal vertical sectional view, taken substantially as indicated by the line 2—2 of Fig. 1.

Fig. 3 is a transverse sectional view, taken substantially as indicated by the broken line 3—3 of Fig. 2.

Fig. 4 is a perspective view, showing one of my bed pans as standing upright upon a flat end which is adapted to serve as an alternative bottom,—one corner being broken away; and Fig. 5, resembling Fig. 2, shows an alternative.

Referring to the details of that specific embodiment of my invention chosen for purposes of illustration, each of my bed pans may comprise a substantially flat main bottom 11, upon which it may rest during use, and substantially flat sides 12. Between these sides may extend a longitudinally rounded member 13, adapted to interfit between the legs of a user and to serve as a partial cover for the bed pan, during use,—this element being shown as provided not only with a central corrugation or "wave" 14 but with a rounded edge 15, which may be substantially semi-circular, as viewed in plan.

At one end of the bottom 11, I show a substantially flat member 16 as constituting a complete closure, interfitting between the mentioned bottom, sides and partial cover; and, at the opposite end of the bottom 11, I prefer to provide a transverse roll 17, integral with the said bottom and interposed between said sides. If desired, a portion of this roll, shown in Fig. 2 as rising not quite to the level of the upper edges of the sides 12, may be slightly flattened, as suggested at 18; but, in any event, this roll is intended not only to be engageable, without discomfort, by the body of the user, and to provide an end wall for the pan, but also to

serve as a full-width pouring edge, over which the contents may be completely removed; and I consider it highly desirable to so extend and recurve this end roll (as best shown in Fig. 2) as to constitute the same an integral handle,—the edge 19 thereof being conveniently engageable by the fingers in the removal of the bed pan from a bed and in the disposition of the same at a bedside, 10 in an upright position such as that illustrated in Fig. 4.

It will be seen from the foregoing that the member 16 is adapted to serve not only as an end closure, during the use of a bed pan 15 embodying my invention, but as an alternative bottom, upon which the bed pan may stand subsequent to its use. The longitudinal rounding of the partial cover 13 (this partial cover being shown as provided with 20 flat areas 20 upon which the legs of the user may rest, with the mentioned "wave" 14 therebetween) and also the semi-circular curvature of the rounded edges 15 are favorable to the use of the central portion of said edge as a spout or partial-width pouring edge, in the emptying of my bed pan.

I emphasize not only the convenience of use of my bed pan, danger of splashing being obviated by the shape of the partial 30 cover 14, and the facility with which the same may be emptied either over the edge 15 or over the transverse roll 17, and the ease and completeness with which the interior may be rinsed and/or scoured and/or 35 inspected, but the very great advantage in providing the described integral handle, so disposed that a patient may conveniently lower the bed pan to a floor, leaving the same in an upright but safe position pending further attention by a nurse or other attendant; and the mentioned handle then 40 serves not only to enable the nurse or attendant to remove the bed pan with one hand, carrying the same in a dependent manner, 45 but conveniently to empty, rinse and stow the same, in readiness for subsequent use.

Although I have above described a single complete embodiment of my invention, it should be understood not only that various 50 features of my invention might be independently employed but also that numerous modifications, aside from mere changes in proportions, appearance or size, might easily be devised by workers skilled in the arts to 55 which this case relates, without involving the slightest departure from the spirit and scope of my invention, as the same is indicated above and in the following claims.

For example, as shown in Fig. 5, in order 60 to cause any contents to flow toward the alternative bottom 16', I may give the main bottom 11' a slight rearward inclination,—and, in this case, the sides 12' may or may 65 not extend below the bottom 11', in such manner as to cooperate with the edge 19' in

supporting the pan and in preventing lateral slippage thereof.

I claim as my invention:

1. A bed pan which is substantially rectangular in plan outline, said bed pan comprising: a main bottom, upon which it may rest during use; an end wall which is adapted to serve as an alternative bottom, when said bed pan is shifted to an upright position; and additional walls,—said main bottom being provided, at the end opposite said alternative bottom, with a transverse roll forming a handle. 75

2. A bed pan comprising: substantially flat sides connected by a longitudinally rounded member which is adapted to serve as a partial cover; and a substantially flat main bottom terminating at one end in a transverse roll forming a handle and at its opposite end in a member which is adapted 85 to serve as an alternative bottom.

3. A bed pan comprising: substantially flat sides connected by a longitudinally rounded member which is adapted to serve as a partial cover; and a substantially flat main bottom terminating at one end in a transverse roll and at its opposite end in a member which is adapted to serve as an alternative bottom,—said longitudinally rounded member being provided with flat 95 areas, for engagement by the legs of the user, and with a substantially semi-circular edge, as viewed in plan. 90

4. A bed pan comprising: substantially flat sides connected by a longitudinally rounded member which is adapted to serve as a partial cover; a substantially flat main bottom terminating at one end in a transverse roll forming a handle and at its opposite end in a member which is adapted to 100 serve as an alternative bottom,—said rounded member being shaped to interfit between the legs of the user. 105

5. A bed pan comprising: substantially flat sides connected by a longitudinally rounded member which is adapted to serve as a partial cover; a substantially flat main bottom terminating at one end in a transverse roll forming a handle and at its opposite end in a member which is adapted to 110 serve as an alternative bottom,—said longitudinally rounded member being so shaped as to provide a partial-width pouring edge 115 or spout.

6. A bed pan comprising: substantially flat sides connected by a longitudinally rounded member which is adapted to serve as a partial cover; a substantially flat main bottom terminating at one end in a transverse roll forming a handle and at its opposite end in a member which is adapted to 120 serve as an alternative bottom,—said transverse roll being continuous with said bottom. 125

7. A bed pan comprising substantially flat sides connected by a longitudinally 130

rounded member which is adapted to serve as a partial cover; a substantially flat main bottom terminating at one end in a transverse roll forming a handle and at its opposite end in a member which is adapted to serve as an alternative bottom,—said transverse roll constituting an end of wall of said bed pan when in a substantially horizontal position of use.

10 8. A bed pan comprising: substantially flat sides connected by a longitudinally rounded member, adapted to serve as a partial cover; a substantially flat main bottom terminating at one end in a transverse roll forming a handle and at its opposite end in a member which is adapted to serve as an

alternative bottom,—said transverse roll being adapted to serve as a full width-pouring edge in the emptying of said bed pan.

9. A bed pan comprising: substantially flat sides connected by a longitudinally rounded member, adapted to serve as a partial cover; a substantially flat main bottom terminating at one end in a transverse roll and at its opposite end in a member which is adapted to serve as an alternative bottom,—said transverse roll comprising an integral handle for said bed pan.

In testimony whereof, I have hereunto set my hand at Los Angeles, California, this 6th day of April, 1927.

MARYANN D. SEARS.
